UNITED STATES PATENT OFFICE

1,993,014

CYLINDER FOR INTERNAL COMBUSTION MOTORS

Joseph J. Maseuch, Newark, N. J.

Application June 9, 1932, Serial No. 616,169

4 Claims. (Cl. 123—169)

This invention relates to internal combustion motors.

When an internal combustion engine is operated certain electrical emanations are released from the spark plugs. Where radio receiving and sending equipment is used in close proximity to the internal combustion engine the electrical emanations from the spark plugs interfere with the operation of the radio equipment. This is especially true in aircraft use where the engine and the radio equipment are necessarily located in close proximity. In order to prevent such interference with the radio equipment it is necessary to shield the spark plugs so as to ground any electrical emanations which may be released from the spark plugs.

The object of the invention is to provide a means for perfectly shielding the spark plug so that the electrical emanations are grounded to the cylinder wall. Where removable fittings are used there is a tendency to leakage through the minute spaces between the screw-threaded face of the fitting and the screw-threaded space of the opening into where the spark plug is introduced.

Therefore, one object of the invention is to provide a shielding element which is integral with the wall of the cylinder so as to avoid any possibility of emanations from the spark plug leaking outwardly from the motor so as to interfere with radio receptivity.

A further object of the invention is to provide such a shielding which is easy of construction and which requires a minimum of machining.

A further object of the invention is to provide such an integral shielding element as will cooperate with the securing means of known forms of removable shielding for the top of the plug, and which will permit the easy application of the top shielding to the integral shielding element and retain the same against rotation by reason of the great vibration of the motor,—which is exceptionally pronounced in aviation engine practice.

The invention consists of the construction, combination and arrangement of parts, as herein illustrated, described and claimed.

In the accompanying drawing, forming part hereof, is illustrated a form of embodiment of the invention, in which drawing similar reference characters designate corresponding parts, and in which:

Figure 1 is a longitudinal section through the wall of the cylinder of an internal combustion motor showing the application of the invention;

Figure 2 is a vertical section taken approximately on line 2—2 of Figure 1 through the wall

of the cylinder of a motor, showing the spark plug and top shielding in elevation or plan;

Figure 3 is a fragmentary view of a portion of the cylinder taken approximately on line 3—3 of Figure 2, looking in the direction indicated by the arrows, but showing the spark plug in plan; and,

Figure 4 is a fragmentary detail in enlarged section through the flange of the shielding element.

Referring to the drawing, A designates generally the cylinder wall and piston assembly of a common form of internal combustion motor provided with cooling fins B and an opening C to receive the screw-threaded end of a common form of spark plug D. Suitable electrical connections E are made to the spark plug D and it is shielded on top by a suitable construction F, arranged to be held in position by a bail G. This construction may be of any well known form but preferably of a construction such as shown in my co-pending applications, Serial No. 481,766, filed September 13, 1930, or Serial No. 550,076, filed July 11, 1931, directed to radio shielding per se.

The cylinder head or wall A when it is cast is formed with a projecting wall 5, preferably circular, and surrounding the opening in the wall to receive the spark plug D. The outer end of the wall 5 is provided with an angular flange 6, the under face of which is provided with slots 7, which may be cast at the time the cylinder head or wall A is cast. The slots 7 are adapted to receive the inturned or angular ends 8 of the bail G.

From the foregoing description it will be seen that the shielding element formed by the wall 5 may be produced at the time of casting the cylinder and no machine work or assemblage is necessary. The top shielding F is grounded to the outer end of the wall 5 and any emanations not utilized for the explosion of the fuel are fully grounded to the motor.

Having thus fully described the invention, what is claimed as new and desired to be secured by Letters Patent is:

1. A radio shield for spark plugs comprising the combination of a cylinder head having a circular well formed thereon to surround a spark plug, said well having an inside diameter substantially larger than a spark plug adapted to be received therein, a dielectric cap disposed over the well, said cap having formed thereon a dielectric skirt adapted to extend into the well adjacent the inner wall of the well and a metallic covering on the cap in electrical contact with the well.

2. A spark plug radio shield comprising the

- combination of a cylinder head provided with a spark plug opening, a cylindrical wall formed on said head as an integral part thereof around said spark plug opening, a dielectric cap disposed over the outer end of said wall, said cap having a circular skirt adapted to surround the terminal end of a spark plug seating in said opening and a metallic covering on said cap in electrical contact with said wall.
- 5 3. A spark plug radio shield comprising, in combination, a well formed as an integral part of a cylinder and adapted to surround a spark plug and a shielding cap to cover said well and enclose a spark plug, said cap comprising a dielectric body having an axial bore to receive the upper end of a spark plug and a radial bore to
- receive a spark plug conductor, contact means to connect a conductor with a spark plug and a metallic covering grounded to the well.
4. A spark plug radio shield comprising, in combination, a well formed as an integral part of a cylinder and adapted to surround a spark plug and a shielding cap to cover said well and enclose a spark plug, said cap comprising a dielectric body provided with a dependent skirt extending into the well around a spark plug and having an axial bore to receive the upper end of a spark plug and a radial bore to receive a spark plug conductor, contact means to connect a conductor with a spark plug and a metallic covering grounded to the well.
